UNITED STATES PATENT OFFICE.

WILLIAM W. ROBERTSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

PILE-CUTTING MECHANISM FOR DOUBLE-FABRIC LOOMS.

Application filed August 9, 1927. Serial No. 211,815.

This invention relates to mechanism for cutting the pile in a loom adapted to weave two pile fabrics face to face, such looms being used for instance in the manufacture of 5 pile carpets.

It is the general object of my invention to provide improved mechanism for cutting the pile as the fabric is manufactured and before the fabric leaves the loom.

10 A further object is to provide mechanism by which the two piles will be cut of uniform length and by the use of which the waste in finishing will be reduced to a minimum.

15 My invention further relates to arrangements and combinations of parts which will be hereinafter described and more particularly pointed out in the appended claims.

20 A preferred form of the invention is shown in the drawings in which

Fig. 1 is a sectional side elevation of parts of a loom, embodying my improvements;

25 Fig. 2 is a front elevation of the mechanism shown in Fig. 1;

Fig. 3 is a plan view, partly diagrammatic, and showing the operation of my cutting mechanism;

30 Fig. 4 is an enlarged plan view of the sliding block and the rotary cutter mounted thereon;

Fig. 5 is a sectional side elevation taken along the line 5—5 in Fig. 4, and

35 Fig. 6 is an enlarged side view of the cutter, looking in the direction of the arrow 6 in Fig. 4.

Referring to the drawings, I have shown portions of a loom frame 10 having a breast beam 11 and guide-rolls 12, 13 and 14 for 40 the upper and lower fabrics. A dove-tailed guide-way 15 is formed in the upper face of the breast beam 11 and a cutter block 16 is slidably mounted in the guide-way 15.

45 A cutter disc 20 is mounted on a sheave or pulley 21 pivoted on a stud 22 secured to an arm 23 projecting rearward from the block 16. The disc 20 is positioned at such an elevation that it will engage the pile mid-way between the upper and lower sur-

50 faces of the fabric F, separating the fabric into upper and lower parts F' and F². The lower part F' is guided over the roll 12, while the upper part F² is guided by the rolls 13 and 14. One fabric passes below

the breast beam 11, while the other fabric is 55 spaced above the breast beam, the two portions of the fabric being separated to permit operation of the cutting mechanism between them.

A cord or cable 25 is secured at one end 60 to one end of the sliding block 16, as indicated at 30 in Fig. 3. The cable 25 then passes around a fixed guide pulley 31 at the left hand side of the loom and returns to a guide pulley 32 on the sliding block 16. 65 The cable then passes around the pulley 21 which supports the cutting disc 20 and is then engaged by a second guide pulley 33 on the block 16. From the pulley 33 the cable is led to a fixed guide pulley 34 (Figs. 70 2 and 3) at the opposite side of the loom, from which it passes one or more times around a drum 35 mounted on a shaft 36 rotatable in bearings in the loom frame 10.

The outer end of the shaft 36 may be supported in a bracket 37 positioned outside of the loom frame and independently mounted. From the drum 35 the cable 25 passes to a guide pulley 38 (Fig. 3) and thence to an attachment point 39 on the right hand end 80 of the block 16. A tightening roll 40 (Fig. 3) is mounted on a bell crank 41 pivoted at 42 to the breast beam 11 and forced yieldingly against the cable 25 by a spring 43.

A pinion 45 (Figs. 1 and 2) is fixed to the 85 shaft 36 and is engaged by a segment gear 46 pivoted at 47 on the bracket 37 and having an offset arm 48 extending upwardly from said gear and connected by a link 49 to a crank pin 50 on a crank arm 51 secured to a continuously rotated shaft 52, which may be the usual bottom or cam shaft of the loom. 90

Having described the details of construction of my invention, the method of operation thereof is as follows: As the shaft 52 rotates, the segment gear 46 is oscillated, rotating the pinion 45 and drum 35 alternately in opposite directions. Such alternate movements of the drum 35 cause the block 16 to be drawn backward and forward across the breast beam 11 from side to side of the fabric. 95

As the block is thus moved in opposite directions, the cable 25 will be simultaneously drawn around the pulley 21, rapidly rotating the cutter 20 in one direction or the other, and causing the cutter to sever the 100 105

pile at a point mid-way between the upper and lower surfaces of the fabric F adjacent the point of weaving of the fabric and before the fabric is taken from the loom.

5. The cutter 20, rotating at high speed as it is drawn across the loom from side to side of the fabric, accurately cuts the pile in the predetermined plane and produces a pile of uniform height on both the upper and lower fabric, thus greatly reducing the waste, as the fabric must be trimmed to the length of the shortest pile.

10 Having thus described my invention and the advantages thereof, I do not wish to be limited to the details herein disclosed otherwise than as set forth in the claims, but what I claim is:

- 15 1. In a loom for weaving double pile fabric, a rotatable cutter, a support for said cutter, and means to reciprocate said support and cutter across the loom between the upper and lower plies of said fabric, said reciprocating means directly engaging and simultaneously rotating said cutter.

- 20 2. In a loom for weaving double pile fabric, a rotatable cutter, a support for said cutter, a single cable effective to reciprocate said support across the loom between the upper and lower plies of said fabric, and means to move said cable alternately in opposite directions, said cable being also effective to rotate said cutter by direct engagement therewith as said support is reciprocated.

- 25 3. In a loom for weaving double pile fabric, a rotatable cutter, a support for said cutter, a fixed guideway in which said support is slidable, guide-rolls on said support, a pulley on said cutter, guide-rolls at the opposite sides of the loom, a drum rotatable alternately in opposite directions, and a single cable having its ends secured to said support and having its intermediate portions passing around said guide pulleys, said cutter pulley and said driving drum, whereby said cable is effective to reciprocate said cutter support and to alternately rotate said cutter in opposite directions.

- 40 4. In a pile thread cutter for looms, a rotatable cutter, a movable carrier therefor,

45 and a flexible driver for said cutter and carrier having two different portions thereof moving in opposite directions at the same time, one of said portions being effective to move the carrier and cutter bodily with respect to the fabric being woven and the other portion being effective to rotate the cutter by direct engagement therewith.

50 5. In a pile thread cutter for looms, a rotatable cutter, a carrier therefor movable with respect to the fabric being woven, and a driving member for said carrier and cutter having two different portions thereof movable in opposite directions at the same time, one portion effective to move the carrier in one direction and the other portion being operatively related to the cutter to cause rotation of the latter as the carrier moves.

55 6. In a pile thread cutter for looms, a rotary cutter, a carrier therefor, and a single means for moving the carrier and rotating the cutter, said means being effective to move the carrier and cutter relatively to the fabric being woven and having a portion thereof directly engaging the cutter and causing rotation of the cutter as the carrier moves.

60 7. In a pile thread cutter for looms, a rotary cutter, a carrier therefor, a flexible driver for said cutter bent back on itself to cause one portion to move in a direction opposite to the direction in which the carrier moves, and means to establish direct operative connection between the cutter and said portion of the driver to cause rotation of the cutter as the carrier moves.

65 8. In yarn cutting mechanism for looms, rotary cutting mechanism, a movable support therefor, and flexible means connected to said support and in driving engagement with a part of the cutting mechanism and effective to move the support relatively to the fabric and to rotate the cutter by reason of the direct engagement between said flexible means and the cutting mechanism.

70 In testimony whereof I have hereunto affixed my signature.

WILLIAM W. ROBERTSON.
